UNITED STATES PATENT OFFICE

116,464

DESIGN FOR A STATUETTE OR SIMILAR ARTICLE

Berta Hummel, Siessen over Saulgau, Germany, assignor to W. Goebel, Oeslau near Coburg,
Germany, a limited company of Germany

Application June 24, 1939, Serial No. 85,662
In Germany February 4, 1939

Term of patent 7 years

To all whom it may concern:

Be it known that I, Berta Hummel, a citizen of Germany, residing at Siessen over Saulgau, Wurtemberg, Germany, have invented a new, original, and ornamental Design for a Statuette or Similar Article, of which the following is a specification, reference being had to the accompanying drawing, forming part thereof, in which:

Fig. 2 is a rear elevational view thereof.

I claim:

The ornamental design for a statuette or similar article, as shown.

BERTA HUMMEL.
